GUN MOUNT WITH FOLDABLE FIRING
CONTROL FRAME

John H. Kochevar, Bisbee, Ariz.

Application May 4, 1945, Serial No. 592,052

2 Claims. (Cl. 89—136)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a gun mount. More particularly it relates to a portable mount intended to be emplaced by being simply set upon a flat ground surface for carrying a light caliber antiaircraft gun for free tracking of targets. As a brief designation of such a mount, it may be termed a "ground set mount."

In order that a light caliber gun, such as a cal. .50 machine gun, may be as effective as possible against a variety of targets, and particularly against aircraft, it is desirable that it be mounted in such a manner that it will have free swinging in traverse and elevation or depression through maximum ranges. Likewise, the gun must be characterized by means providing for the control and firing thereof in any of its infinite positions, requisite consideration being given to the safety and comfort of the gunner. In addition, consideration has been here given to other structural details of the weapon with the object of making it easily transportable, of lightweight construction, readily emplaced and stable while firing.

It is accordingly an object of the present invention to provide a gun mount on which a gun may be mounted for free swinging in azimuth and in elevation or depression, particularly in elevation, and in which means are provided for facilitating the firing of the gun at exceedingly low command height regardless of its position on the mount.

It is an important object of the invention to provide a gun mount having an elevator or pedestal in which the mount for the gun is laterally offset from the pivotal mount of the elevator on the base so that the breech of the gun may be swung as closely as possible to the elevator or pedestal to permit the achievement of maximum elevation.

Among other objects, advantages and features of invention, held in view are the following:

a. To effect a mount construction whereby the gun may be trunnioned with a low center of gravity so as to reduce material and weight of pedestal and secure great stability in proportion to material required, and to reduce the required radius of a polypod mount.

b. Adaptation of the gun to be elevated close to the zenith and traversed through 360 degrees in azimuth by a standing or squatting soldier, notwithstanding that the gun trunnions are much

2

below waist level, and that a simple single member pedestal is employed.

c. To construct an exceedingly light weight mount which will afford a gun support of adequate rigidity for safe and stable pointing of the gun during rapid fire.

d. To embody a mount with the foregoing qualities which is specially adapted to be made readily and quickly into a small package readily portable as a unit and which may safely be dropped by parachute from an airplane, as well as rapidly assembled.

e. To enable operation of the gun alternatively at will by a foldable extension grip and trigger or conventionally by grip and trigger immediately at the back plate or butt of the gun receiver.

f. To attain special fitness in an antiaircraft gun and mount for use by airborne troops.

g. To eliminate interference of mount legs with movements of a gunner in traversing the gun.

The invention has for another important object the provision of firing control mechanism including a firing control frame foldable with respect to the gun and mount during transport and for certain types of firing, and extensible to facilitate firing of the weapon at maximum elevation; in this respect, the invention has for another object means for releasably retaining or locking the firing control mechanism in either position.

Other objects of the invention are to provide a mount of lightweight and sturdy construction; to provide a mount that may be easily disassembled for transport and quickly assembled or set up for firing; and to provide operating mechanism including a plurality of firing grips by which the weapon may be fired from more than one point on the firing control means.

The foregoing and other objects will become apparent from the following detailed description of a preferred embodiment of the invention, and modifications thereof, as illustrated in the accompanying sheets of drawings in which:

Fig. 1 is a side elevation of the mount with a gun positioned thereon and further with the gun shown in its position of maximum elevation as indicated in broken lines; the figure also shows in broken lines the folded position of the firing control means;

Fig. 2 is a plan view of the mount shown in Figure 1, the gun having been omitted from the figure;

Fig. 3 is a longitudinal sectional view on an enlarged scale taken on the line 3—3 of Fig. 2 and showing the details of construction of the

firing control mechanism and operating means therefor;

Fig. 4 is a fragmentary perspective view showing the foldability and extensibility of the frame structure comprising the firing control means;

Fig. 5 is a view similar to that shown in Fig. 3 but illustrating a modified form of operating mechanism for the firing control means;

Fig. 6 is a fragmentary view of the structure shown in Fig. 5 on the line 6-6 of Figure 5, 10 looking in the direction of the arrow;

Fig. 7 is a fragmentary perspective view of the rear end portion of the gun illustrating generally the actuating member operable by the firing control means on the mount.

The particular embodiment of the invention chosen for the purposes of the present description comprises a base 10 preferably formed as a casting and having a plurality of horizontally disposed sockets 11. In the present instance there are four sockets which serve to receive respectively the inner ends of four supporting legs 12. Each socket 11 is provided with quickly releasable and attachable clamping means 13 by which the legs are readily and quickly attached to or detached from the base 10. Each leg is provided at its outer end with a spade 14 which is adapted to engage the ground in the usual manner to stabilize the base 10. That is to say, the spades may be pressed into ordinary earth by the gunner's foot, and the legs 12 will then rest upon the ground directly. The spades prevent sliding of the mount or rotation thereof. The legs may be pressed down also, so that the bed plate forming the bottom of the base 10 may be adjusted on the ground surface, sustaining a substantial load and affording a more stable support. Similarly when the gun is set on an earth pier with a surrounding annular trench of the same radius as the spades, the legs—by reason of their approximately horizontal positions and the function of the bottom of the base 10—may be adjusted so as to come to rest firmly on the top of the pier, whereas with inclined leg construction, they crumble off the edges of the pier and cause upset of the gun, or delay and impair its emplacement accommodation. Usually such mounts involve such command height that if the span of the foot portions is reduced to avoid interference with the gunner, the gun will be too unstable for use. A wide radius of legs precludes the practicable use of a gun for antiaircraft fire in a protective annular trench of the kind indicated, as well as impairing its use on ordinary fields, by interfering with movements of the gunner in tracking.

The gun mount further includes a generally upright elevator or pedestal 15 having a lower mounting portion 16 angled with respect to the vertical and mounted rotatably on the base by means of a bearing indicated generally at 17. The intermediate portion of the elevator 15 comprises a vertical column 18 formed with a vertical bore (not shown) within which is received the vertical shank (not shown) of a mounting yoke 19. The upper end of the column 18 is formed as a flange 20 having a transverse recess 21 into which the lower portion 21' of the yoke 19 fits. This construction mounts the yoke 19 on the elevator 15 for rotation as a unit about the vertical pivot 17 between the elevator 15 and the base 10. A securing clamp 22 is threaded into the side of the column 17 and engages the shank of the yoke 19 for removably and rigidly securing the yoke and elevator together.

The yoke 19 is curved upwardly and in the di-

rection toward the axis of the bearing 17 so that the latter is offset with respect to the column 18 and is provided at the upper end of each of the bifurcations forming the yoke with a pair of trunnions 23, aligned on a common horizontal axis. These trunnions serve as means by which a cradle 24 is carried by the yoke 19 for vertical swinging about a horizontal axis with respect to the base 10 and elevator 15. The cradle 24 is preferably of integral construction and includes a pair of longitudinally spaced transverse bottom or web portions 25 (Fig. 2), at opposite sides of each of which is an upstanding wall portion 26 extending longitudinally or normal to the axis of the trunnions 23. The rear end of the cradle 24 is provided with means, such as a pair of oppositely disposed bolts 27 passed respectively through the side walls 26, by which the cradle 24 carries a rearward extension 28. For the purposes of the present disclosure, the cradle 24 and extension 28 will be considered as part of the same unit, the importance of the connection between the cradle 24 and the extension 28 by the bolts 27 lying only in the fact that the bolts 27 may be removed for disassembly of the cradle components. The cradle extension 28 includes a pair of opposite rearwardly diverging frame portions 29 having parallel rear ends, provided with downwardly extended parallel parts 29' rigidly cross connected by a transverse frame portion 30. The right-hand frame member 29 (as viewed from behind the gun) includes a laterally extending manipulating or gun-pointing grip 31. The left-hand frame member 29 is provided with a combined manipulating and operating grip 32 (Fig. 2) for operating the firing mechanism of the gun as well as aiding in gun pointing. The grip 32 is rockably mounted on the left-hand frame portion 29 by means of a shaft or bolt 33, the inner end of which has keyed thereto, or otherwise secured thereto for rocking therewith, a lever arm 34 (Fig. 3). This arm 34 is pivotally connected by an adjustable link 35 to a bell crank 36, carried on a pivot 37 on a vertical extension support 38, at the left side of the cradle extension 28. The extension support 38 carries thereon an actuator indicated generally at 39. This actuator may be of any conventional construction and includes a longitudinally reciprocable, spring-pressed plunger 40, the outer end of which is pivotally connected by a short link 41 to the bell crank 36. Rocking of the bell crank 36 on its pivot 37 is imparted by the link 41 to the plunger 40, which in turn effects longitudinal reciprocation of an actuator plate 42 provided with an actuating lug 43. As will be hereinafter brought out in detail, the actuator 39 is operatively associated with the firing mechanism of a gun mounted on the cradle.

Each of the frame portions 29 of the cradle extension 28 is directed upwardly at its rearward end to provide a vertical frame member or support stud 44 (Fig. 4). The supports 44 serve to carry thereon a firing and gun pointing frame extension indicated generally at 45 (Fig. 3). This extension may be termed a gun operating frame, and comprises a pair of transversely spaced tubular members 46, each of which is provided at one end with a longitudinal slit 47. As best shown in Figs. 1 and 4, the members 46 are respectively mounted on the supports 44 of the frame portions 29 by means of pivot pins 48, the lower portions or corners of the supports 44 respectively fitting into the slit portions of the members 46 so that the extension frame 45 may be swung

from a position folded beneath the cradle 24 (broken lines in Fig. 1) to the upright or gun operating position shown in Figs. 1 and 3, for example. The upper end of the extension frame 45 is provided with a transverse member 49 rigidly cross connecting the members 46. The upper right-hand side of the extension frame 45 is provided with a manipulating or gun pointing grip 50, which may be similar to the lower manipulating grip 31. The upper transverse member 49 of the extension frame 45 is provided with a transverse bracket 51, which has formed integral therewith a pair of transversely spaced upwardly extending ears 52, in which is carried a transverse rod 53. One end of the rod projects at the right side of the extension frame 45 and serves as means by which the manipulating grip 50 is secured to the extension frame. The other end of the rod 53 projects at the left side of the extension frame 45 and carries rockably thereon a combined manipulating or gun pointing and operating or gun firing grip 54, similar to the operating or gun firing grip 32 previously referred to. The manipulating grips are rigid members by which swinging of the gun in tracking is effected, and the other two, while aiding in the swinging of the gun, in addition serve as triggers or gun actuators, firing the gun. The rod 53 carries thereon, intermediate the grip 54 and proximate ear 52 of the bracket 51, a sleeve 55 formed with a depending lever arm 56. An operating rod or link 57 is provided at its upper end with a clevis through which a bolt or pin 58 is passed to connect the rod or link 57 pivotally to the arm 56 on the sleeve 55. The inner end of the manipulating and operating grip 54 is keyed or otherwise secured to the sleeve 55 so that the rocking of the grip 54 effects rocking of the sleeve 55 and arm 56. The operating link 57 extends downwardly and is curved inwardly and then again downwardly so that it lies within the extension frame 45, and is provided at its lower end with a clevis 59 and pin 60 for pivotal connection to a lever arm 62 carried loosely on the pin or bolt 33 previously described as carrying the manipulating grip 32 and lever arm 34. The lever arm 34 carries rigidly thereon a projecting stud or pin 63 engageable by the underside of a hooked nose portion 64 thereover formed on the forward end of the lever arm 62.

From the description thus far, it will be seen that rocking of either of the grips 32 or 54 will effect actuation of the link 35, bell crank 36 and actuating plate 42. Rocking of either of the grips 32 or 54 to reciprocate the actuating plate 42 is in a clockwise direction, as viewed from the right side of the mount. Because of the lost motion connection 63-64 between the lever arm 34 and the lever arm 62, the actuator plate 42 may be reciprocated by the lower manipulating grip 32 independently of movement of the upper grip 54.

It was previously stated that it was an important object of the invention to provide firing control means mounted for movement from a folded position beneath the cradle to an upright position extending away from the cradle. The frame extension 45 just referred to comprises such firing control means and is mounted for movement between the two positions by means of the pivotal mounting of the members 46 on the extension support 44. For this purpose, the common axis of pins 48 is coincident with the axis of pin 60. Because of the slots 47 in the members 46, the extension frame has free movement with respect to the cradle extension 28. The internal diameter

of the tubular members 46 is equal to the width of the supports 44. This arrangement provides for the construction and use of a simple means for releasably securing the extension frame 45 in its upright position as illustrated in Figs. 1 and 3. This securing means includes a pair of sleeves 65, one being slidably carried on one tubular member 46, and the other being similarly carried on the other tubular member 46. As illustrated in Figs. 1, 3 and 4, the sleeves 65 are adapted to embrace the lower portions of the members 46 and the respective extension supports 44, so that, when the extension frame 45 is in its upright position, the extension supports will be confined within the slots 47 of the member 46, and within the downwardly positioned sleeves 65. Release of the frame extension 45 for swinging movement downwardly is effected by upward positioning of the sleeves 65 so that the extension supports 44 may be freed from their locked positions with respect to the members 46. As shown in broken lines, the frame extension 45 may be folded (Fig. 1) beneath the cradle 24 and cradle extension 28. The right-hand frame member 29, 25 of the cradle extension 28, is provided with releasable securing means in the form of a spring clip 66 engageable with the right-hand tubular member 46 when the frame extension 45 is moved to the lower position indicated.

As shown in Fig. 1, the cradle 24 is provided with a pair of longitudinally spaced transversely extending removable mounting pins 67 and 68 which pass through openings in the opposite side members 26 of the cradle 24 and into mounting openings in the receiver 9 of the gun carried by the mount. The mounting of the gun on the cradle, as just described, is of a well known type and need not be set forth in greater detail. The gun 8 illustrated is shown generally in the patent to Browning, No. 1,628,226, and is the only machine gun of .50 caliber used in all branches of the Army, and Air Forces of the United States in the present war. Various adaptations to special uses were made in which the proportions of the receiver and gun mechanism remained the same in all cases. The form illustrated has a quick dismountable barrel 8, the fastenings of which comprise no novel part of the present invention, and therefore are not illustrated although useful for compactness when the gun is shipped in knocked down form, especially when it is to be dropped from airplanes. In the latter use it is usually accompanied by airborne troops (one of the important uses made of this gun and mount).

Fig. 7 illustrates in perspective the rear and left side of the receiver 9 of a conventional type machine gun. There is illustrated in this figure means, other than the usual trigger, for actuation of the firing mechanism of the gun. This actuating means may assume any desired form. That herein illustrated is but one of many conventional types and is therefore not shown in connection with the interior mechanism of the gun. In brief, the adapter means of the type herein shown is connected to the firing mechanism inside the receiver of the gun and includes a reciprocable lug 69 at the exterior left side of the receiver. When the gun is mounted on the cradle 24, the lug 69 is aligned with and behind the actuating lug 43 on the actuator plate 42 at the left side of the cradle 24. Accordingly, when either of the grips 32 or 54 is rocked, the lug 69 on the receiver of the gun is reciprocated to effect firing of the gun in the same manner as if the

single actuating trigger, usually provided on the gun, had been utilized.

In the modified form of firing control mechanism shown in Figs. 5 and 6, the essential differences over the construction shown in Figs. 1, 2 and 3 are in the manipulating grips and the actuating linkage. In the modified form the extension frame 45 is provided at its right side with the upper manipulating grip 50 and the cradle extension 28 is provided at its right side with the manipulating grip 31.

The cradle extension 28 is provided at its left side with a rigidly mounted manipulating grip 70 which is substituted for the rockable combined operating and manipulating grip 32. The grip 70 has pivotally mounted thereon a depressible lever 71 which is provided at its inner end with a downwardly and inwardly curving actuating member 72 engageable with a lip 73 preferably formed integrally with a longitudinally extending lever 74. This lever is rockably mounted on the left-hand frame member 29 by means of a pin or bolt 75 and takes the place of the lever arms 34 and 62 of the construction shown in Fig. 3. The lever 74 is connected at its forward end to a link 76 which is in turn connected to the bell crank 36. The rear end of the link 74 is pivotally connected by means of a clevis 77 and pin 78 to a vertically extending operating rod 79, the upper end of which is pivotally connected to the inner end of a depressible handle or lever 80, pivotally carried on an upper manipulating grip 81 on the extension frame 45. The grip 81 is rigidly carried by the left-hand tubular member 46 of the frame 45 and takes the place of the rockable grip 54, previously described in connection with the construction shown in Fig. 3. It will be noted that either of the levers or handles 71 or 80 may be pressed to effect actuation of the linkage comprising the rod 79, lever arm 74, link 76 and actuator mechanism 36-43. In other words, each grip 70 or 81 and respective lever 71 or 80, provides a grip that may be squeezed by the operator for firing the gun.

The use and operation of the weapon is substantially the same whether the extension frame 45 be equipped with either the rockable manipulating grips 54 and 32 or with the squeezable grips 70-71 and 80-81. When the weapon is emplaced for general firing in which the field of fire is mainly horizontal, the extension frame 45 may be folded to the position shown in broken lines in Fig. 1, in which position it will be retained by the releasable securing means comprising the securing clip 66. This would be the practice in case the gunner is seated or prone on the ground on which the mount is set, and also in case the mount is set on the pier formed by an annular trench in which the gunner may stand just beyond the ends of the legs. It may be seen that the legs have a radius which closely approximates that of the extremity of the cradle extension with respect to the axis of traverse of the gun. In use on a trench pier as mentioned, if there is liability of "strafing" by enemy airplanes, the gunner may keep the extension frame erected and locked, so that he may change from use of the lower grips 31-32, to use of the grips 50-54 at will for overhead targets, without interruption of tracking. Even though the extension frame 45 is in this position, there will be no interference with the functioning of the firing control mechanism as operated by the lower left-hand grip 32 (70-71). The arrangement of the opposed grips 31 and 32 (70-71) is such that the operator may

track the weapon by grasping one grip with each hand and may aim the weapon or continue tracking with his right hand on the right-hand grip 31 while rocking the left hand grip 32 (squeezing the grip 70-71) with his left hand. It will be noted from an examination of Fig. 1 that even with the extension frame 45 folded beneath the cradle 24, the gun will still have a relatively large range in elevation. The offset relationship between the upper and lower mounting portions of the elevator 15 with respect to the intermediate portion thereof provides for this maximum elevation and at the same time there is no interference whatsoever with the ability of the weapon to track in azimuth.

It will be noted that the arrangement between the firing control linkage and the pivotal mounting of the extension frame 45 is such that the extension frame may be swung from one of its positions to the other without any interference with the linkage. This result follows from the coincidence of the extension frame mounting pivot 48 and the pivot 60 between the vertical rod 57 and the lever arm 62 (Fig. 3).

The same relationship between pivots occurs in the construction shown in Fig. 5, wherein the pivotal mounting 48 of the frame extension 45 is coincident with the pivot 78 forming the connection between the vertical arm 79 and the rockable lever arm 74.

When the gun is used as an antiaircraft weapon, it will be found desirable to extend the frame 45 to its upright position. As previously stated, it may be locked in this position by the securing sleeves 65. Since the firing of the weapon in defense against aircraft will necessarily involve firing at or near maximum elevation of the gun, tracking and firing of the gun will be accomplished through use of the upper grips 50 and 54 (80-81). This position of the extension frame 45, as extended, will enable the operator to track the weapon with considerable ease and even at maximum elevation of the weapon he will be required to assume, at most, the relatively comfortable squatting position. In such position his feet will be free of the legs 12 on the base 10 so that he can move freely about the mount without tripping over the legs of the mount.

In case the gun is mounted in a revetment or analogous trench form, the folded arrangement of the extension frame may be used while the gun is set on an earth pier. For airborne attack operations, however, such emplacements are usually impossible and the extension frame, coordinated with the low mount has been found of marked value.

In the training of such weapons, on moving targets, heretofore, correction for proper lead has customarily been derived principally from observation of tracer paths, and this practice can be readily carried out with my improvement. The initial lay of the gun may be estimated from the same factors heretofore governing antiaircraft fire with open sight guns, and carried out as in operating firearms "from the hip." In squatting, as may happen in case of extreme elevation of the weapon, the gunner remains on his feet and ready to rise if necessary. He may step laterally while in this squat position to accommodate azimuthal changes of angular position of the target.

The invention has been used with .50 caliber machine guns of a form previously standard, which is illustrated in Figure 1.

From the proportions of the gun used on this mount it will be seen that the height of the trun-

nions (which are nearly even with the bore axis) above the ground is approximately 27 inches, whereas, with a single grip set gun, in which the grips are immediately at the rear of the receiver it has heretofore been thought necessary to have the trunnions at a height of 60 inches for antiaircraft fire. While it has heretofore been found practicable to adapt a lower mount to antiaircraft fire, the best required an elaborate system of trigger framing and four sets of triggers and grips, while the present device has eliminated much of the bulk, weight, and grip devices heretofore used on those mounts. The prior lowest portable antiaircraft tripod mount adapted for the particular gun illustrated had a trunnion height of 36 inches. Said mount weighed 313 lbs.; the instant mount weighs 125 lbs.

Improvements looking to the simplification and reduction of weight of an antiaircraft machine gun mount for use by airborne troops have lately been attempted, owing to the need for rapidly bringing such weapons into action by newly landed airborne troops in the open while exposed to enemy fire. The best prior development submitted proposed a sixty inch trunnion height, weighed 165 lbs. and required at least fifteen seconds longer to set up for action. It was found too unstable for adoption. These attainments together and separately are factors of high importance each and all marking valuable advances.

An important advantage derived from the lowering of trunnion height in such a gun is, that it has been possible to shorten the radius of the legs and spades (as in Figures 1 and 2) so that the gunner, in operating the gun, may move in a circular path beyond the spades, and so will not trip or stumble over the legs of spades, which has been a serious difficulty with the prior developments of portable antiaircraft tripod mounts for such a weapon as here shown.

Although I have shown and described a preferred embodiment of my invention, with one modification thereof, it will be apparent that other modifications and alterations may be made in these preferred forms of the invention without departing from the spirit and scope thereof as defined in the appended claims.

I claim:

1. A gun mount for machine guns and the like, comprising a gun cradle having right and left rearwardly diverging frame portions terminating rearwardly of a gun mounted in said cradle, a generally rectangular extension frame comprising parallel side members and a transverse member rigidly connecting said side members adjacent one of their ends, each said side member being pivoted at its other end, on a common first axis, upon the rear end of a respective frame portion, whereby said extension frame may be pivoted from a first upright position at the rear of and extending above said gun, to a second position beneath and closely adjacent said cradle, a lower grip carried by one said frame portion, a first lever pivoted on said one frame portion on a second axis, means responsive to pivotal movement of said first lever in one direction only to fire a gun carried by said cradle, an operating connection between said lower grip and first lever, a

second lever pivoted on said second axis, a lost motion connection between said levers whereby motion of said second lever in said one direction only correspondingly pivots said first lever, an upper grip on said extension frame having a part pivoted on a third axis, and a link connected to said part at one end and pivoted at its other end to said second lever on an axis normally coincident with said first axis, whereby either grip may be used to fire said gun.

2. A gun mount for machine guns and the like, comprising a gun cradle having right and left rearwardly diverging frame portions terminating just rearwardly of a gun mounted in said cradle, a generally rectangular extension frame comprising parallel side members and a transverse member rigidly connecting said side members at one of their ends, each said side member being pivoted at its other end on a common first axis, upon the rear end of a respective frame portion, said first axis being transverse of a gun mounted in said cradle, whereby said extension frame may be pivoted from a first substantially vertical position with said transverse member above the level of a gun in said cradle, to a second position wherein said frame is underneath and closely adjacent said cradle, right and left lower grips on said frame portions forwardly of said first axis, one said lower grip being pivoted on a second axis parallel with said first axis, a lever connected with said one lower grip, means responsive to pivoting of said lever in one direction to fire a gun mounted in said cradle, a second lever pivoted on said second axis and adjacent said first lever, a lost motion connection between said levers whereby pivoting of said second lever in said one direction only also pivots said first lever, right and left upper grips on said frame above said transverse member, one said upper grip being pivoted on a third axis, and a link connection between said pivoted upper grip and said second lever, said link connection being pivoted to said second lever on an axis normally coincident with said first axis whereby said extension frame may be pivoted to said second position without affecting said levers.
